Primary Examiner — Sanjeev Paul*Assistant Examiner* — Rene H. Kadoo(74) *Attorney, Agent, or Firm* — Banner & Witcoff, Ltd.(57) **CLAIM**

The ornamental design for a handle for a kitchen appliance as shown and described.

DESCRIPTION

FIG. 1 is a front perspective view of a handle for a kitchen appliance showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is enlarged view of the claim as shown in FIG. 1 with environment removed for clarity purposes.

The broken line showing of the remainder of the handle and the elements on the rear surface of the handle mount forms no part of the claimed design.

1 Claim, 7 Drawing Sheets(56)
